UNITED STATES PATENT OFFICE.

HAROLD CLAUDE HARPER, OF DETROIT, MICHIGAN.

WINDOW GUARD.

Application filed May 18, 1921. Serial No. 470,721.

To all whom it may concern:

Be it known that I, HAROLD CLAUDE HARPER, a citizen of the United States, and a resident of Detroit, in the county of Wayne and State of Michigan, have invented certain new and useful Improvements in Window Guards, of which the following is a specification.

My invention relates to devices adapted for use in conjunction with windows for guarding the window when in open position against persons or objects entering or falling therethrough, a purpose of my invention being the provision of a guard of this character which is of extremely simple and inexpensive construction and which in applied position in a window is capable of occupying an inactive and active position in which it successfully spans an open window for the purpose described.

I will describe one form of window guard embodying my invention and will then point out the novel features thereof in claims.

25 In the accompanying drawings:

Figure 1 is a view showing in front elevation a window and window casing having applied thereto one form of window guard embodying my invention.

30 Figures 2 and 3 are vertical and transverse sectional views taken on the lines 2—2 and 3—3, respectively, of Figure 1.

Figure 4 is a fragmentary detail perspective view of a portion of the guard frame and one of the hinges.

Similar reference characters refer to similar parts in each of the several views.

Referring specifically to the drawings and particularly to Figures 1 and 2, I have here 40 shown a conventional form of window casing designated at K in which are mounted for vertical sliding movement two window sashes designated at S and S'.

The window guard forming the subject 45 matter of my invention comprises in the present instance a frame designated generally at F which is of rectangular outline and is made up of longitudinally extending bars 15 and transversely extending bars 16 which connect the first bars at regular spaced intervals throughout their length. The frame F is formed of any suitable metal or other material with the bars 15 and 16 preferably formed integral with 50 each other so that the frame as a whole could be stamped or molded with one opera-

tion. The outermost transverse bars 16 are provided adjacent their lower ends with semicircular recesses 16^a through which the lips 17 of retaining lugs L are adapted to 60 pass. As illustrated to advantage in Figure 3, the lugs L are constructed from single lengths of metal bent to form the lips 17 which are arranged in spaced relation to a base 18, with the latter provided with 65 screw receiving openings.

The frame F carries at its lower edge hinges H, one leaf 19 of which is formed integral with the frame while the leaf 20 is hingedly connected to the first leaf and 70 formed with screw receiving openings.

In the applied position of the window guard as shown in Figures 1, 2 and 3, the two lugs L are secured to the vertical portions of the lower window sash S and in 75 such manner that the lips 17 occupy reverse positions. By means of the hinges H, the frame F is hingedly supported upon the sill of the window casing K, screws extending through the openings of the leaves 80 20 and secured within the window sill so that the frame can occupy an inactive position as shown in dash lines in Figure 2 or an active position as shown in solid lines in the same figure. In the inactive position of the frame, it occupies a vertical 85 position at the inner side of the window casing, the leaves 19 and 20 permitting of the frame occupying this inactive position.

In the active position of the frame, it lies 90 parallel and contiguous to the lower sash S, the lugs maintaining the frame in this position by so adjusting the sash S so as to permit of the lips 17 being passed from the outer side of the frame through the recesses 16^a to the inner side of the frame so 95 that the frame is confined between the lips and the window sash in the manner clearly shown in Figure 3. The construction of the lugs L is such as to allow of unrestricted 100 sliding movement of the sash S with respect to the frame while at the same time maintaining the lips in embracing position to the frame so that the latter is maintained in active position irrespective of the 105 position of the sash.

By this arrangement it will be seen that with the frame in active position, the sash S can be moved to any vertical position, and that when raised, the frame will serve to 110 guard the opening formed thus preventing the passage of objects through the open win-

dow. It is to be understood that the construction of the frame may be varied to provide relatively large or small spaces between the vertical bars 16, and that these 5 openings can be spanned by screens so as to prevent the passage of smaller objects therethrough.

When it is desired to discontinue the use of the guard, it can be swung to inactive 10 position by moving the sash S so that the lips 17 will register with the recesses 16^a thus permitting the lips to disengage the frame so that the latter can be swung downwardly to inactive position.

15 The outermost bars 16 are provided at points above the recesses 16^a with openings 21 designed for the purpose of receiving oversize hooks (not shown) which are adapted to be secured to the window sash in the 20 event one desires to permanently secure the window guard to the window.

Although I have herein shown and described only one form of window guard embodying my invention, it is to be understood 25 that various changes and modifications may be made herein without departing from the spirit of the invention or the spirit and scope of the appended claims.

What I claim is:—

30 1. A window guard comprising a frame consisting of upper and lower horizontal members connected by spaced vertical mem-

bers, said lower horizontal member being adapted to be hingedly attached to the sill of a window casing and one of said vertical 35 members being provided with a recess in one edge thereof, and a lug adapted to be attached to the lower sash of the window in position to move through said recess when the sash is lowered and to embrace the said 40 vertical member when the sash is raised.

2. A window guard comprising a frame formed with recesses, hinges carried by the frame, and lugs insertable through said recesses to engage or disengage the frame and 45 movable bodily in embracing relation to the frame when in engagement therewith.

3. A window guard comprising a frame including parallel vertical bars formed with recesses in the inner edges thereof adjacent 50 to their lower ends, hinges carried by the frame for attaching the latter to the sill of a window casing, and lugs adapted to be secured on the lower sash of the window in position to move through said recesses when 55 the sash is lowered and when the frame is swung toward said sash until parallel therewith, whereby said lugs will embrace the vertical members of said frame when the lower sash is moved vertically in such a 60 manner as to permit sliding movement of the sash within certain limits.

HAROLD CLAUDE HARPER.
